AERIAL TOY DRIVE

Original Filed Dec. 18, 1924

FIG. 1.

FIG. 2.

JOHN HOLTZMAN

INVENTOR

BY *O. Holtzman*
his ATTORNEY.

UNITED STATES PATENT OFFICE

JOHN HOLTZMAN, OF NEW YORK, N. Y.

AERIAL TOY DRIVE

Original application filed December 18, 1924, Serial No. 756,718. Divided and this application filed January 26, 1928. Serial No. 249,623.

My invention relates to toys and especially to the mechanism embodied in a toy aircraft for operating the latter and imparting to it the appearance of an aircraft in flight.

5 The present application is a division of my copending application for Letters Patent, filed Dec. 18, 1924, Serial No. 756,718.

10 The object of this invention is to provide a toy of this character, which is simple and sturdy in construction and which may be manipulated by a small child to send the craft on its outward and return flights without the child changing his or her position.

15 I accomplish these objects by means of the construction described in the following specification, set forth in appended claims and 20 illustratively exemplified in the accompanying drawings, in which Fig. 1 is a side elevational view of a toy air craft embodying my improved propelling mechanism; Fig. 2 is a bottom plan view of the same.

25 Referring to the drawings, 10 denotes a longitudinally disposed bar which forms the body of the craft. The rear or tail of the bar 10 is provided with an inclined support 11 having its opposite ends clamped about the said bar. An elevating plane 12 is arranged on the support 11, the plane 12 being preferably in the shape of an elongated ellipse. The 30 front of the bar 10 carries a fixed wing 13 on its upper side, the supporting piece therefor being similar to that used for the elevating plane 12. A hollow propeller shaft 14 is suspended and rotatably mounted in brackets 15 35 carried by the bar 10 forward of the fixed wing 13. The craft is provided with a propeller 16 having a hub 17 fixed on the extreme forward end of the propeller shaft 14.

40 In addition to the bar 10, the frame comprises a U-shaped metal portion 18, the closed end of which abuts the forward bracket 15 at the end of the bar 10, while the parallel sides 19 are spaced from and project well below the sides of the bar. Rotatably mounted 45 between and in the sides 19 are three spaced spindles 20, 21 and 22, the spindle 20 being nearest the tail is provided with a spur gear 23, operating adjacent one of the sides 19. Between the gear 23 and the opposite side 19 50 the spindle 20 carries a coiled spring 24, one

end of the latter being fixed in the gear 23 and the other in the side 19, as illustrated in Fig. 2.

55 The intermediate spindle 21 carries a spur gear 25 in mesh with the spur gear 23 and between the gear 25 and the opposite side 19 the spindle 21 carries a winding drum 26 which is stepped, the larger portion 27 being arranged adjacent the gear 25 and the smaller portion 28 projecting from 27 to the opposite side wall 19. The steps 27 and 28 of the drum receive the coils of two cords 30 and 29, respectively. The ends of the cords 29 and 30 are attached to their respective steps of the drum adjacent their outer ends and wind towards the center when the drum rotates in one or the other direction. The other end of the cord 29 projects towards the tail of the machine beneath the bar 10 and is guided in its movements in eyes 31 and 32 mounted between the tail ends of the sides 19 and extreme 60 tail tip of the bar 10, respectively. The other cord 30 from the step 27 passes directly to and through the bore of the hollow shaft 14, as 65 illustratively exemplified in Fig. 1.

70 The speed of the air craft over the cords 75 29 and 30 in one direction is governed by the propeller 16, which receives its rotary motion from the spring 24 on its return travel through a spur gear 33 mounted and turning with the spindle 22, and a worm gear 34 disposed intermediate the latter and in mesh with the worm threads 35 cut in the exterior of the propeller shaft 14.

75 To manipulate the toy, the cord 29 at its free end is securely attached to some stationary object, while the cord 30, which in normal position is substantially all wound upon the portion 27, is drawn outwardly. As a result 80 the cord 30 unwinds from the drum and the cord 29 winds upon the portion 28, as the drum revolves in a clockwise direction. Corresponding rotary motion is imparted to the spur gear 23 by rotary movement of the gear 21 which in turn tensions the spring 24. The propeller during its outward travel is rotating in the reverse direction to that of driving through the worm and worm wheel connection with the shaft 14. The air craft thus far has traveled over its cords and is positioned adjacent the fixed end of cord 29. The 85 90 95 100

5 tension on the cord 30 is then relieved, where-
upon spring 24 through the train of gears
23, 25 and 33 exerts its tension to rotate the
spindles 20, 21 and 22 in the opposite direc-
tions from those taken during their initial
movements. The propeller 16 now oper-
ating exerts its pull in a direction towards the
operator and as a consequence the craft re-
turns to its initial position, the cord 29 being
10 unwound from the drum 26 and cord 30 be-
ing again rewound upon the latter. It will
be clear then that by the simple operation of
alternately exerting and releasing tension on
the cord 29 the device will move towards and
15 away from the operator with all the appear-
ances of an air craft in flight and without the
necessity of a change in the position of the
operator.

I claim:

20 1. In a mechanical toy of the character
described, the combination of a frame, a
winding drum mounted in the frame, a hol-
low propeller shaft mounted in the frame and
operatively associated with said drum, and
25 a cord one end thereof being wound about
said drum and the other projecting through
the bore of the shaft to operate the toy.

2. A mechanical toy of the character de-
scribed, the combination of a frame, a wind-
30 ing drum mounted in the frame, a hollow
propeller shaft mounted in the frame and
operatively connected with the said drum,
and a pair of cords with one of their ends
35 wound about said drum, one cord projecting
from the drum towards one end of the toy
and the other cord projecting from the drum
through the bore of the shaft to operate the
toy.

3. A mechanical toy comprising a bar, a
40 frame attached thereto, a worm spindle re-
volvable in said frame, a propeller fan fixed
to said spindle, said spindle being hollow,
a gear mounted in the frame to actuate the
spindle, a drum fastened to the gear, a cord
45 fastened with one end to the drum and the
other passing through the spindle to operate
the toy.

4. A mechanical toy comprising a frame,
50 a threaded spindle revolvable in said frame,
a propeller fan fastened to said spindle, said
spindle being hollow, a gear mounted in the
frame to actuate the spindle, a drum in said
frame adjacent to said gear, and a pair of
55 cords with one of their ends fastened to the
drum, their windings so disposed that when
one cord is winding the other is unwinding
on the drum and one of the free ends of said
cords passing through the hollow spindle to
60 operate the toy.

5. In a mechanical movement having the
combination of a frame, a hollow spindle re-
volvably mounted in said frame, a gear in
the frame to drive the spindle, a cable pass-
65 ing through the hollow spindle to operate

the same, and a fan propeller fastened to
said spindle.

6. A mechanical toy having the combina-
tion of a frame, a hollow spindle revolvably
70 mounted in said frame, a gear to drive the
spindle, a cable passing through the hollow
spindle and driving the gear, a fan propeller
fastened to said spindle, and a second cable
to drive the gear and spindle in opposite di-
rections to operate the toy.

7. A propelling mechanism for toy air
craft, comprising a hollow propeller spin-
dle, a drum operatively associated with said
spindle, and cords winding in opposite direc-
80 tions upon said drum, one cord being pro-
jected through the spindle to rotate the drum
and to operate the toy in one direction.

8. In a mechanical toy air craft comprising
a propeller, a drum operatively associated
with said propeller for actuating the same,
85 and cords winding in opposite directions
upon said drum to operate the toy.

9. In a mechanical toy aircraft compris-
ing a fan propeller, a drum, a pair of cords
90 wound in opposite directions upon said drum
and means interposed between said drum and
propeller for actuating the same upon the
pulling one of said cords.

10. In a mechanical toy comprising the
combination of a frame, a fan propeller re-
volvably mounted in said frame, a drum, a
95 pair of cords wound in opposite directions
upon said drum, and means interposed be-
tween the drum and the propeller to operate
the toy upon pulling one of said cords.

In testimony whereof I affix my signature.
JOHN HOLTZMAN.
